UNITED STATES PATENT OFFICE.

GEORGE BRAND, OF SOUTHFIELDS, NEW YORK.

SPRING-MOUNTED BED-BOTTOM.

SPECIFICATION forming part of Letters Patent No. 674,364, dated May 21, 1901.

Application filed June 27, 1900. Serial No. 21,773. (No model.)

To all whom it may concern:

Be it known that I, GEORGE BRAND, a citizen of the United States, and a resident of Southfields, in the county of Orange and State 5 of New York, have invented certain new and useful Spring-Mounted Bed-Bottoms, of which the following is a specification.

This invention relates to an improvement in bed-bottoms for bedsteads, and has for one 10 object to increase the comfort of the user and particularly to improve in this direction those bed-bottoms wherein a resilient fabric is stretched from one end of the bed-bottom to the other.

15 Another object of the invention is to add to any form of bed-bottom a resiliency that shall extend equally to all parts thereof.

With these objects in view the invention consists in the formation, construction, and 20 combination of parts hereinafter described and claimed.

In the accompanying drawings, which form a part of this specification, Figure 1 shows in plan a bed-bottom equipped with my improved device. Fig. 2 shows in perspective one corner of a bed-bottom with my improvement attached thereto, and Fig. 3 shows a modified form of such improvement.

In bed-bottoms having a woven wire top or 30 flexible top supported resiliently at the ends of the bed-bottom there is no resiliency at their ends. In order to add resiliency to such bed-bottoms at their ends and to make such added resiliency extend through the entire 35 bed-bottom, I secure at each corner of the bed-bottom a resilient device by which it may be supported upon the bedstead. Such device may vary greatly in its formation and mode of attachment. It is preferable, however, to so construct it that the desired amplitude of movement for the bed-bottom may be obtained without raising the same too far above the average height of other bed-bottoms. This may best be accomplished by the 40 device illustrated in Fig. 2. Therein an elbow-lever 4 is shown as pivoted at its angle to the side rail 5 of a bed-bottom. The lower end of the lever 4 is preferably provided with a projection, as 6, for engagement with the 45 side rail of a bedstead. From the upper arm of the lever a spring, preferably in spiral form, as shown at 7, extends to the end of the

bed-bottom, to which it may be attached in any suitable manner, as by connecting with a staple or eye 8, formed upon or secured to the 55 end rail 9 of the bed-bottom or, preferably, the upper end of the corner-piece 10. To limit the movement of the lever 4 in response to the tension of said spring, any suitable stop may be employed. One conveniently formed for 60 this purpose is shown at 11, and consists of a lug projecting laterally from the corner-piece 10.

In the place of the lever and spring just described any other resilient device or spring 65 may be employed—such, for example, as a plate-spring 12. (Represented in Fig. 3.) This spring may be connected to a lug, as 13, formed on the side of the corner-piece 10 and provided with suitable pins or projections 14 70 at its ends for engagement with the side rail of a bedstead. The end pieces 9 of the bed-bottom may be stopped in their descent in any suitable way, as by their coming to rest upon said lever, as at 16, or upon the side rail, 75 if preferred. It is immaterial whether the side rails of the bed-bottom are metal and of the form illustrated or whether they be of wood. It is also immaterial whether the side rails of the bedstead (indicated at 15) are of 80 metal or of wood. The bed-bottom equipped with my device will operate the same under any of these circumstances.

Other changes in the formation and construction of parts and their association with 85 one another may be made without departing from the spirit of the invention.

I claim as my invention—

1. The combination with a bed-bottom, of a lever pivoted thereto at each corner thereof, 90 a spring connecting one end of each lever to said bottom and means at the lower end of each lever for engaging a bedstead and supporting the bed-bottom thereon.

2. A bed-bottom provided at each corner 95 with an elbow-lever pivoted to the side rail thereof and adapted to engage with the side rail of a bedstead for the support of said bottom, and a spring connecting the upper arm of each lever to the bed-bottom, as and for 100 the purpose set forth.

3. The combination with a bed-bottom, of a lever at each corner thereof pivoted to the side rail of the bed-bottom and having a lug

21
at its lower end for engagement with the side rail of a bedstead, a spring connected to one arm of the lever and to the end of the bed-bottom, and a lug extending from the bed-bottom and serving as a stop to limit the movement of the lever, as and for the purpose set forth.

Signed at New York, in the county of Orange and State of New York, this 23d day of June, A. D. 1900.

GEORGE BRAND.
